CLEANING PAD FOR WINDSHIELDS

John W. Anderson, Gary, Ind., assignor to Productive Inventions, Inc., a corporation of Indiana

Application July 29, 1947, Serial No. 764,343

17 Claims. (Cl. 15—121)

1

The present invention relates generally to cleaning devices and more particularly is directed to a pad, embodying improved principles of design and construction, for cleaning automotive windshields and other surfaces.

The prompt and effective cleaning of windshields at gasoline service stations is desirable in that it saves the time of the attendant and the customer and promotes safe driving by improving driving vision through the windshield.

Many different materials and methods have been employed in an effort to obtain maximum results. Materials and methods which serve with reasonable satisfaction under ordinary conditions fail to perform effectively under extreme conditions frequently encountered as a result of seasonal influences.

Among the most difficult extraneous matter necessary to remove from windshields are dried bug anatomy, sticky sap-like deposits excreted from trees, road muck splashed by passing cars from sloppy, dirty pavements, and oil film deposited on the windshield in various ways, including the careless use of oily rags for wiping windshields, the use of oily solvents sprayed on the windshield to facilitate cleaning, and oil mist deposited from the vapor of the exhaust of cars ahead in traffic, particularly from cars the motors of which are pumping oil.

Contrary to the popular conception, commercial glass such as is used in windshields, has a degree of porosity, which adds to the difficulty of removing extraneous matter. Perhaps the most stubborn of all such matter is oil film and similar films which accumulate, slowly and almost imperceptibly, but which cause smearing under the windshield wiper blade the instant it begins to storm and the wiper is put into operation.

Experience has taught that, properly supplemented, under certain conditions, water is in all respects the best fluid for use in cleaning windshields, in part because it provides adequate lubrication for the cleaning device and also readily accepts the extraneous matter, in suspension or in solution.

Various devices for use with water have been practiced but all have been lacking in some particular characteristics essential to maximum results.

One particular object of the invention is to provide a cleaning pad comprised of felt or equivalent material provided with means in the form of supporting elements of a unique character which are constructed and arranged to assist in readily removing from the glass even

2

the most stubborn of extraneous matter of all kinds.

An important object of the subject invention is to provide a device with intercommunicating internal cavities to provide a reservoir so that an extra supply of water may be effectively stored to assist in the scouring or cleaning operation, principally in two ways. The water in the reservoir feeds out by capillarity through the felt members on either side of the supports. Without the supply of water in the reservoir, the only water available would be whatever water might soak into the felt from its outer surfaces. Secondly, water from the reservoir may be released by the operator, when needed, by the simple expedient of rolling or lifting the finger or thumb from all or a part of the area of the side vents shown. All the cavities are intercommunicating and communicate with each of the vents 16.

It will be noted in one of the modifications of the invention that walls formed by holes through the wick member 3 and by the two supports 4 and 5 form enclosed cavities into which water may pass through strainers. This action tends to filter or screen from the water any dirt or other extraneous matter, so that there is supplied, to the wick and other felt members, water substantially clear and readily capable of penetration by capillarity through the wick to the surface to be cleaned.

Another object of the invention is the provision of squeegee or wiping members for wiping or removing all the surplus water from the surface of the glass without the use of a cloth, chamois, paper towel or any other separate device. In other words, the device embodies all of the elements essential to scouring, cleaning, and drying of the glass to promote clear vision.

A further important feature of the invention lies in providing means for holding parts of the device, particularly the felt and supporting elements, against displacement, as it is essential that the cleaning face, or edge, of the felt and supporting elements be maintained substantially in predetermined positions for effective contact with the glass.

Other objects and advantages of the invention reside in its simplicity of structure, economy of manufacture and assembly, durability, and reliability of performance.

Additional objects and advantages of the invention will become apparent after considering the description hereinafter set forth in conjunction with the drawing annexed hereto.

In the drawing, Figures 1 through 12 illustrate

the preferred embodiment or construction of the invention, Figure 1 illustrating a top view of the assembly, portions of which have been broken away to show structural details;

Figure 2 is a longitudinal sectional view taken substantially on line 2—2 of Figure 1;

Figure 3 is an end view of the pad showing its application to a surface to be cleaned;

Figure 4 is an end view of the pad similar to Figure 3 showing one of the squeegee or wiping elements associated therewith in the act of wiping a surface to be cleaned;

Figures 5, 6, 8, 9, 10, and 12 exemplify detail characteristics of parts common to both embodiments of the invention, Figure 5 being a top view of one of the two side plates;

Figure 6 is a sectional view taken substantially on line 6—6 of Figure 5;

Figure 7 is a perspective view of one of a pair of strainers or filters which preferably form parts of the assembly;

Figure 8 is a perspective view of one of a pair of retaining members;

Figure 9 is a perspective view of the wick or inner layer or ply of water absorbent material;

Figure 10 is a perspective view of one of a pair of squeegee elements;

Figure 11 is a perspective view of one of four supports preferably constituting parts of the assembly;

Figure 12 is a perspective view of one of a pair of outer layers or plies of felt-like material;

Figure 13 is a top view of a second embodiment of the invention, portions of which have been broken away to better illustrate structural details;

Figure 14 is an end view of the device of Figure 13 showing its application to a surface to be cleaned;

Figure 15 is a longitudinal sectional view taken substantially on line 15—15 of Figure 13;

Figure 16 is a perspective view of one of a plurality of members of a particular character which may be employed as a combined abrader and filter element; and

Figure 17 is a perspective view of one of a plurality of members similar to the one illustrated in Figure 16.

As exemplified in Figures 1 through 12 of the drawings, there is held securely between alternate layers 1, 2, and 3 of water conducting felt or other water absorbing or conducting material, a pair of relatively thin flexible dirt-removing supporting elements 4 and 5, preferably constructed from some desirable commercial plastic material, which present their edge extremities to the surface to be cleaned, substantially in the plane of the outer edges or working faces of the felt.

The felt members are preferably formed with a row of four aligned transverse openings to provide chambers 6, 7, 8, and 9 which serve as a reservoir for the internal storage of water. The aggregate of the areas of the walls of the holes through the felt expose a maximum of the felt to the absorption of water from the reservoir.

Retaining members 10 are preferably positioned against the exterior surfaces of the outer layers of felt and are preferably provided with a row of four interned tubular means 11 which engage the openings in the outer layers of felt for the purpose of resisting displacement thereof.

A pair of corresponding supporting elements 12 are positioned against the retaining members 10 and also engage portions of the outer layers

of felt as depicted in Figure 2. Strainers 13 bear against the supports 12.

Substantially flat pieces of rubber 14 or other similar resilient pieces of material overlie the strainers 13 and supports 12 and serve as squeegees. Side plates 15 bear against the rubber. Vent openings 16 are provided in the side plates and are preferably communicatively connected with the chambers 6 through 9, through a row of three apertures 17 provided in each rubber piece, and rows of three apertures in the supports.

The felt, supports, retaining members, strainers and rubber squeegees are held securely in operative position by the side plates and bolts or rivets 18 which extend through holes provided therefor in the parts of the device to maintain the entire assembly in operative relationship. Rivets 18 have at each of their ends a flared-over portion which engages adjacent side plates 15, respectively, offering no resistance to a movement of the side plates 15 toward each other under normal pressures for the purpose of facilitating discharge of water outwardly from the felt members 1, 2, and 3.

The supports 4 and 5 are spaced apart by the intermediate layer of melt 3 which acts as a wick. Water entering the reservoir and space between these supports is closely screened and filtered by the strainers 13 so that extraneous matter does not pass freely into such reservoir and/or space. This is important because the water in such reservoir may carry a minimum of suspended matter which might find its way into the reservoir chambers due to possible failure on the part of the operator to maintain clean water in which to keep the device submerged. By filtering the water which enters the reservoir, that water flows more freely down the wick 3 and outwardly through the outer felt layers toward the windshield to assist in lubricating the cleaning action and in keeping all the supports free from extraneous particles.

Between uses the device is kept submerged in water. In submersion the felt becomes saturated and the reservoir fills with water. The operator may close the vent holes in the side plates with thumb and finger, if desired, to retain a maximum supply of water for heavy duty service. In the operation of the device, a part of the water from the reservoir passes through the felt to assist in lubricating the supports and in keeping them flushed free from extraneous particles, perhaps sufficiently abrasive to scratch the windshield if retained and embedded. The outer edges of the supports are disposed preferably in or under the plane of the outer edges of the two squeegees when their relative positions have been established by use of the device. Only under extreme conditions is it necessary to apply to the device enough pressure to cause the supports actually to contact the glass.

As the device is drawn across the windshield, as exemplified in Figure 3, under normal cleaning pressure, the felt and supports are flexed or displaced. Under the pressure required to remove extraneous matter, the felt, squeegees and supports have a tendency alternately to relieve their pressures against each other and/or slightly separate. This movement not only facilitates the self-cleaning action of the wet parts or members in contact with the glass but also provides a device in which the parts may separately or jointly laterally adjust themselves to irregularities in the glass, thereby improving the effectiveness of the device.

ness of the cleaner. It will be apparent that the opposite longitudinal working face or edge 19 of the device may be used to advantage in cleaning a surface that may not be sufficiently dirty to require the use of the edges of the rubber, the supports, or the constrained felt adjacent the opposite working face. It will be evident that the end working faces or edges 20 of the device may also be employed for convenience in reaching restricted areas.

In the event that additional water is required for the surface of the windshield, the operator may facilitate its discharge from the reservoir by the simple act of sliding or rolling a thumb and/or finger slightly to open one or both of the vents 16. If the reservoir becomes empty and the water absorbing members are well saturated, an additional supply of water for cleaning purposes may be obtained by merely squeezing inwardly such members to compress the felt and free any excess of water. Such squeezing action also serves to flush and clean the members of foreign matter. The operation of loosening completely all extraneous matter from a large and stubbornly fouled windshield with this device is accomplished readily in less than 60 seconds. Attention is directed to the fact that by reversing the movements of the device alternately when in contact with the glass, the wet felt also alternately presses against and departs from the supports so that a pumping or suction action takes place against the supports. This action further assists to prevent accumulation of extraneous matter on the supports. Such accumulation is also prevented by the supplying of water through the capillary action of the felt members—particularly through the intermediate felt member 3 which spaces the supports 4 and 5 apart.

It is to be understood that valved vents of well known types, other than those illustrated, may be satisfactorily employed to control the flow of water from the reservoir.

Under conditions where speed in cleaning, accompanied by maximum clarity of the glass after cleaning, is desirable, as at very busy gas stations where often hundreds of windshields are cleaned in a single working day, the squeegee elements 14, in cooperation with other parts of the assembly, enable the operator, once all the extraneous matter on the windshield has been loosened, to quickly squeegee the glass under heavy manual pressures, which pressures compel a substantially complete removal, from the surface of the glass, of all water and all matter in solution or suspension, leaving the glass in condition to provide clearer and safer driving vision.

It will be noted that one of the longitudinal edges 21 of each squeegee is disposed substantially in the plane of one of the two working edges or faces of the device. The other longitudinal edge 22 of each squeegee is disposed a distance remote from the plane of the opposite edge or face of the device. The work ends of each rubber squeegee are preferably disposed in or near the plane of the working ends of the device.

Thus there is presented, at the longitudinal edges 21, effective squeegees. These squeegees are made more effective and more resistant to maximum working pressures by the supports 4, 5 and 12 and the felt members against which they rest. The combination of the limited resilience and of the accelerating resistance of the felt as the rubber is flexed against it, and the resilience of the rubber, plus the spring-like action of the

supports, provides a unique construction having high utility as a squeegee because much greater pressures can be applied by the operator in the course of the squeegee operation than would be possible where there are no resilient abutments for the rubber as described. The adjacent supports 12 serve respectively as spring-like supports for the inner sides and the wiping edges of the squeegees 14, and serve also to hold the felts

10 1, 2 and 3 against mashing out of shape. In the course of usage over a long period the felt members and the supports tend to wear. To readily permit this wear with a minimum of interference, the opposite edges 22 of the rubber elements may be disposed a substantial distance away from the plane of the longitudinal edge or face 19 of the device as mentioned above. It will be noted, however, that these opposite edges lie beyond and outside of the side plate so as to prevent such wear from finally exposing the edge of such plate to the glass. It is desirable that the side plates be made substantially rigid in character in order to impart stability to the device.

25 The squeegee elements enable the operator to remove substantially completely from the glass at a single stroke and with no perceptible residue left on the glass, all water and other matter. The preferred operation is first to bring the squeegee horizontally across the topmost portion of the glass. Accumulated matter is wiped off the squeegee by stroking of a cloth held in the opposite hand of the operator between each stroke of the squeegee. The second stroke is lower on the windshield and slightly overlaps the area covered by the first stroke so that no streaking occurs. The strokes are continued until the bottom of the windshield is reached, whereupon the operation is completed.

30 40 45 50 55 Without the use of the squeegee elements above described, it is necessary for the operator to remove the water and extraneous matter either with a separate squeegee, which means he must lose time and motion in discarding one tool and picking up the other, or the operator must clean the glass with a rag or a paper towel or some similar device. Rags used to wipe windshields become loaded quickly with matter from the windshield and must be laundered or discarded. This creates added cost. When fouled rags are continued in use as usually happens, they tend to leave behind on the windshield a film usually containing oil-like substances. That film clouds the glass under the wiper blade when a storm begins and the wiper is put into operation. This clouding or smearing of the glass often continues for several minutes, jeopardizing the safety of the vehicle, its operator and its passengers.

60 65 70 Paper towels must be discarded after one use. Thus is created extra cost and waste, which is prevented by the use of the subject invention when equipped with squeegee elements as above described.

In the embodiment of the invention exemplified in Figures 13 through 17 of the drawing, the parts illustrated in Figures 5, 6, 8, 9, 10, and 12 are employed, including pairs of abraders 23 and 24, the latter being used in lieu of the supports forming parts of the preferred construction. In this embodiment there is held securely between the alternate layers of felt, a pair of corresponding woven relatively thin abraders 23, preferably metallic, which present their abrasive extremities to the surface to be

cleaned substantially in the planes of all of the outer edges or working faces of the device. An additional pair of corresponding metallic abraders 24, of a width somewhat less than that of the abraders 23, are preferably disposed between the rubber squeegees and felt cleaning members so that one longitudinal edge of each abrader 24 is arranged to engage the surface to be cleaned. Otherwise described, the extremities of all four abraders are presented for abrasive action adjacent one longitudinal working edge or face of the device including the end working faces, whereas the opposite longitudinal face is provided with only one pair of abraders. The abraders 24 also support the felt members and serve to filter the water prior to its entry into the reservoir and the abraders 23 provide means for further filtering the water entering the intermediate wick member. The abraders are preferably cross-woven and may take the form of a wire screen of a character which will not scratch the glass. To prevent fraying and to expose a maximum of strands at the edges of the device, the abraders are so constructed and arranged that substantially all strands are positioned preferably at substantially a 45 degree angle to the surface of the windshield when normally in contact therewith. This arrangement of strands greatly facilitates the performance of the device and greatly prolongs its efficiency. In the operation of the device, a part of the water from the reservoir follows the woven abraders to assist in lubricating their action and in keeping them flushed free from extraneous particles, perhaps sufficiently abrasive to scratch the windshield if retained and embedded. More specifically in this respect, a portion of the water in the reservoir moves toward the outer edges of the abraders through capillary action of the small alternately offset interstices between strands of the abraders, all of which additionally assists in lubricating and flushing them clean.

While I have shown and described my invention in connection with certain specified embodiments, it will, of course, be understood that I do not wish to be limited thereto, since it is apparent that modifications may be made in such embodiments and the materials thereof without departing from the spirit and scope of my invention as set forth in the appended claims.

I claim:

1. A cleaning device comprising a center ply member of felt material, relatively rigid members engaging the outer faces of said center member and supporting the latter, outer ply members of like material engaging the outer faces of said supporting members, additional relatively rigid supporting members engaging the outer faces of said outer ply members, squeegee members engaging the outer surfaces of said supporting members, side plates engaging said squeegee members, and rivet means extending through said members and connected to said plates for holding the members assembled.

2. A cleaning device comprising a body of felt material provided with a reservoir, a flat strainer provided adjacent said reservoir, a squeegee element and a side member arranged in a flat condition with said body, an aperture provided in said side member and in said squeegee element communicating with said reservoir, and means passing through said body and connected to said side member for holding the body, strainer and squeegee assembled.

3. A cleaning device comprising superimposed layers of felt, transverse openings provided in said layers forming a reservoir for water, a scraper member arranged between said layers and intersecting said reservoir, and means extending through the device spaced from its marginal edges for securing the layers and member in assembly.

4. A window cleaning device comprising a body of felt provided with a pair of working faces for engaging a surface to be cleaned, members arranged substantially within the confines of said body for supporting same and having edges disposed substantially in the same planes as the working faces of the body, and a rubber squeegee overlying one side of the body, one edge of said squeegee being disposed substantially in one of the planes aforesaid for wiping the said surface and another edge spaced from the other plane to expose a side portion of the body for contact with such surface.

5. A cleaning pad of a size to be embraced by the hand, said pad comprising a body of felt provided with a pair of working faces for engaging a surface to be cleaned, members arranged substantially within the confines of said body for supporting same and having edges disposed substantially in the same planes as the working faces of the body, a squeegee overlying one side of the body, one edge of said squeegee being disposed substantially in one of the planes aforesaid for wiping the said surface and another edge spaced from the other plane to expose a side portion of the body for contact with such surface, a reservoir for water provided in said body, a side plate overlying said squeegee and provided with a vent engageable by a digit of the hand for controlling the flow of water from the reservoir to the operating faces of the body, the edges of the supporting members, and to said one edge of said squeegee, and means passing through said pad for holding the parts in assembly.

6. A cleaning device for windows comprising a body constructed of superimposed layers of felt, a relatively rigid dirt-removing element arranged between and supporting said layers, an opening provided in one of said layers, side plates overlying the outer surfaces of said layers, means passing through said side plates, said layers, and said dirt-removing element for holding the same assembled, and means disposed between said one layer and one of said side plates cooperating with the opening in said layer acting to prevent displacement of such layer.

7. A cleaning device comprising a substantially flat wick member, a pair of dirt removing members overlying the opposite sides of said wick member, a pair of water absorbent members overlying said dirt removing members, opening provided in said absorbent members and said wick member forming a reservoir for water, retaining members engaging said absorbent members and provided with means engaging the openings in said absorbent members assisting to prevent displacement of the latter, squeegee members bearing against said retaining members and provided with apertures communicating with the reservoir, side plate members abutting said squeegee members and provided with vents engageable by an operator to control the flow of water from the reservoir through the wick member and absorbent members, and means extending through the device and connected to the said side plate members for holding all of the members in assembly.

8. A cleaning device comprising a body of felt or the like, a dirt removing member carried by said body, a reservoir for water in said body, and a wick arranged alongside said dirt removing member, said member providing means for filtering the water prior to its entry into the reservoir and passage into the wick.

9. A cleaner assembly comprising a substantially flat wick provided with a transverse opening, and dirt removing elements of stranded material disposed across the ends of said opening for filtering water that may pass into said opening.

10. A cleaning pad for windows comprising a water-absorbent body, provided with a face 15 adapted to engage a surface to be cleaned, a woven wire screen member disposed in said body and arranged so that substantially all of the ends of the strands along one edge of such member are disposed adjacent the face of the body for engagement with a surface to be cleaned.

11. A cleaning device for windows provided with felt-like water-absorbing members between which is held a substantially flat woven wire screen dirt removing member having substantially rectangular mesh and comprised of two interwoven series of parallel strands and having a substantially straight edge constructed and arranged to contact, adjacent the plane of the edges of said felt members, said series of strands each 30 being normally arranged at an angle with relation to the edge of said dirt removing member and in the plane of said member.

12. A cleaning device comprising a pair of water absorbent members, a dirt removing element disposed therebetween, a retaining member engaging one of said members, a strainer engaging said retaining member; a squeegee element engaging said strainer, a side plate engaging said squeegee element, a vent provided in the side 40 plate through which liquid may enter and pass through the strainer and means extending through the parts aforesaid for holding the same assembled.

13. A cleaning device comprising a center ply of felt material, dirt removing members engaging the opposite sides of said center ply, an additional pair of felt plies engaging said dirt removing members, retaining members engaging the outer faces of said additional felt plies, strainers engaging said retaining members, squeegee elements engaging said strainers, side plates engaging said squeegee elements, a vent provided in each side plate through which liquid may enter and pass through the strainer, and means extending through the parts aforesaid for holding the same assembled.

14. A generally rectangular cleaning pad comprising three stacked layers of water absorbent material, supports of nonabsorbent material for said layers disposed on opposite sides of the intermediate layer, resilient squeegee members arranged at the outer sides of the outer layers, plates overlying the squeegee members, and means connected to said plates for holding the layers, supports, members and plates assembled.

15. A cleaning device comprising layers of felt, a member disposed between and supporting said layers, one of said layers being provided with an opening through which a liquid may enter into such layer, side plates, an aperture in one of said side plates whereby liquid may pass into said opening, and a pair of independent means, solid in cross-section, extending through and connecting the plates for holding the layers, member and plates together.

16. A cleaning device comprising layers of water-absorbent material, openings forming a reservoir in said layers, members engaging said layers and provided with tubular portions projecting into said openings for holding the members and layers against relative movement, side plates, and means connected to said side plates and extending through the said openings for fastening the layers, members and side plates together.

17. A cleaning pad comprising layers of water-absorbent material, a relatively rigid scraper of non-absorbent material disposed between and supporting said layers, members engaging said layers to maintain said layers in a predetermined 25 relationship, resilient squeegee elements arranged in a flat condition with said layers, and a pair of spaced means extending transversely through said layers, said scraper, and through said squeegee elements for holding the same assembled.
